UNITED STATES PATENT OFFICE.

GEORGE E. WILLIAMS, ANDREW J. CAMPBELL, AND DAVID H. BRAND, OF TRENTON,
NEW JERSEY.

TOILET ARTICLE.

1,034,177.

Specification of Letters Patent. Patented July 30, 1912.

Application filed July 29, 1911. Serial No. 641,309.

To all whom it may concern:

Be it known that we, GEORGE E. WILLIAMS, ANDREW J. CAMPBELL, and DAVID H. BRAND, citizens of the United States, and 5 residents of the city of Trenton, in the county of Mercer and State of New Jersey, have invented an Improvement in Toilet Articles, of which the following is a specification.

10 This invention relates to toilet articles and the principal object of the same is to provide a device having a containing tray mounted upon a standard and braced by resilient arms, the cover of the tray forming a polishing buffer.

15 This invention is illustrated in the accompanying drawings, wherein:

Figure 1 is a side elevation of the receptacle. Fig. 2 is a side elevation of the upper portion of the powder receptacle and polish holder with the cover forming the polisher removed from the polish holder and shown in section. Fig. 3 is a top plan view of the receptacle with the polisher in 20 place. Fig. 4 is a view similar to Fig. 3 with the polisher removed. Fig. 5 is a bottom plan view of the polisher. Fig. 6 is a section taken along the line 6—6, Fig. 1.

25 Referring to the accompanying drawings by numerals it will be seen that this invention comprises a bottle 10 in which the tooth powder is kept. This bottle may be formed of any suitable material such as glass or metal and may be of any desired shape. A collar 11 is mounted upon the neck of the bottle and is provided with an opening 13 through which the powder passes out of the bottle. A cap 12 is mounted upon the collar and is provided with an opening 13 which is adapted to be brought into registry 30 with the opening formed in the collar 11 so that the powder may pass from the bottle when desired. A tray 14 is mounted upon

the cap 12 and forms the receptacle for the nail polish 15. Spring bracing arms 16 are 45 secured to the tray 14 and have their lower ends 17 connected with the cap 12, thus securely bracing the tray and preventing danger of its becoming broken from the cap. A cover 18 fits upon the tray 14 and is provided with an enlarged upper plate 19 which forms a receptacle for the padding 20 and covering 21. This padding and covering forms the nail polisher or buffer and the cover 18 forms a handle for the buffer. 50 It will thus be seen that there has been provided a receptacle for the tooth powder upon which there is mounted a second receptacle in which the polishing paste is mounted and that the cover of the receptacle 55 for the polishing paste forms a buffer.

What is claimed is:—

1. A device of the character described comprising a supporter, a tray carried by the upper end of said supporter, resilient 65 bracing arms secured to opposite sides of said tray and having their lower ends connected with said supporter, and a cover for said tray.

2. A device of the character described 70 comprising a standard, a containing tray mounted upon said standard, a cover for said tray, said cover comprising a collar fitting upon said tray, a plate secured to said collar, and provided with side flanges, and 75 a buffer mounted upon said plate and fitting within the flanges of said plate.

In testimony whereof, we have signed our names to this specification in the presence of two subscribing witnesses.

GEORGE E. WILLIAMS.

ANDREW J. CAMPBELL.

DAVID H. BRAND.
